Primary Examiner — Robert M Spear*Assistant Examiner* — Ryan Harvey(74) *Attorney, Agent, or Firm* — Fox Law Group, LLC;
 Bradley Fox(57) **CLAIM**

I claim the ornamental design for a treadmill for use with a desk, as shown and described.

DESCRIPTION

FIG. 1 is a perspective view of a treadmill for use with a desk of the present design;

FIG. 2 is a top view of the treadmill for use with a desk of FIG. 1;

FIG. 3 is a top view of the treadmill for use with a desk of FIG. 1 without environmental elements for clarity of disclosure;

FIG. 4 is a front view of the treadmill for use with a desk of FIG. 1; and,

FIG. 5 is a rear view of the treadmill for use with a desk of FIG. 1.

The broken (dashed) lines shown in FIGS. 1 through 5 are included only for the purpose of illustrating environmental elements, and form no part of the claimed design.
